(57) **CLAIM**

The ornamental design for the boot, as shown and described.

DESCRIPTION

FIG. 1 is a perspective view of the first embodiment of a boot showing our new design.

FIG. 2 is a right-side perspective view of the first embodiment.

FIG. 3 is a left-side perspective view of the first embodiment.

FIG. 4 is a front perspective view of the first embodiment.

FIG. 5 is a rear perspective view of the first embodiment.

FIG. 6 is a top perspective view of the first embodiment; and, FIG. 7 is a bottom perspective view of the first embodiment. The broken lines including the stitching on the boot represent unclaimed environment and form no part of the claimed design.
